CLAIM

The ornamental design for a display module for smart phone, as shown and described.

DESCRIPTION

FIG. 1 is a front, left perspective view of the display module for smart phone showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a front, right perspective view thereof, shown in an alternate state; and,

FIG. 9 is a front, left perspective view thereof, shown in an alternate state.

The broken lines showing the remainder of the display module for smart phone are directed to environment; the broken lines form no part of the claimed design.

1 Claim, 9 Drawing Sheets

Related U.S. Application Data

continuation of application No. 29/664,135, filed on Sep. 21, 2018, now Pat. No. Des. 890,152.
